[57] CLAIM

The ornamental design for a turbine cover, as shown and described.

DESCRIPTION

FIG. 1 is a right side view in elevation of the turbine cover;
FIG. 2 is a left side view in elevation of the turbine cover;
FIG. 3 is a top plan view;
FIG. 4 is a bottom plan view; and,
FIG. 5 is a side view in elevation of the installed turbine cover.

The broken line showing of a turbine is for illustrative purposes only and forms no part of the claimed design.
